FIG. 1 is a front elevational view from the upper right side of the book and magazine display showing my new design;

FIG. 2 is a rear elevational view thereof; and

FIG. 3 is an enlarged fragmentary sectional view taken in the direction of the arrows on line 3—3 of FIG. 1. The cross line shading which is partially shown in FIGS. 1 and 2 is understood to represent conventional fabric and to repeat uniformly across the front and back sides of the rear surface.
